UNITED STATES PATENT OFFICE.

WILLIAM J. SCHWARZ, OF BROOKLYN, NEW YORK.

DESIGN FOR A GAS-STOVE.

SPECIFICATION forming part of Design No. 35,738, dated February 11, 1902.

Application filed January 8, 1902. Serial No. 88,934. Term of patent 7 years.

To all whom it may concern:

Be it known that I, WILLIAM J. SCHWARZ, a citizen of the United States, residing at Brooklyn, in the county of Kings and State 5 of New York, have invented and produced a new and original Design for Gas-Stoves, of which the following is a specification, reference being had to the accompanying drawings, forming part thereof, in which—

10 Figure 1 is a perspective front view of my newly-designed gas-stove, and Fig. 2 an end view thereof.

As shown in the drawings, the leading or material feature of my newly-designed gas-stove 15 comprises a bottom horizontal base portion a , a top horizontal base portion b , vertically-arranged cylindrical members c , and a horizontal top portion d , which is placed on the vertically-arranged cylindrical members c and 20 which is provided with a flaring base d^2 , a vertical front portion d^3 , and a back portion d^4 , which is segmental in cross-section. The bottom base portion a is provided with lugs a^2 , and the sides thereof are curved in cross-section, as shown at a^3 , said base portion being 25 narrower at the top than at the bottom, while the top base portion b at the front and back is curved or segmental in cross-section, as shown at b^2 , and the vertically-arranged members c are provided with openings c^2 , and the top portion or member d is also provided with openings d^5 and a segmental ornamental plate d^6 . The bottom base member a is also provided at the front thereof with openings a^4 , and the ends and sides thereof are flared outwardly and downwardly, as shown at a^5 , and the ends of the top base portion b are vertical, while the top surface thereof is flat and uniform throughout. 30 35

Having thus fully described my invention, 40 what I claim as new, and desire to secure by Letters Patent, is—

The design for a gas-stove as herein shown and described.

In testimony that I claim the foregoing as 45 my invention I have signed my name, in presence of the subscribing witnesses, this 31st day of December, 1901.

WILLIAM J. SCHWARZ.
